(57) **CLAIM**

The ornamental design for a catheter tip, substantially as shown and described.

DESCRIPTION

FIG. 1 is a perspective view of an embodiment of a catheter tip.

FIG. 2 is an enlarged perspective view of the catheter tip of FIG. 1.

FIG. 3 is a front view of the catheter tip of FIG. 1.

FIG. 4 is a first side view of the catheter tip of FIG. 1.

FIG. 5 is a back view of the catheter tip of FIG. 1.

FIG. 6 is a second side view of the catheter tip of FIG. 1; and, FIG. 7 is a top view of the catheter tip of FIG. 1.

The portions of the drawings shown in broken lines form no part of the claimed design.
